UNITED STATES PATENT OFFICE.

JOSEPH HUFNAGEL, OF PORTLAND, OREGON.

DESIGN FOR AN EMBLEMATIC STAND.

Application filed August 1, 1921. Serial No. 489,117. Term of patent 7 years.

To all whom it may concern:

Be it known that I, JOSEPH HUFNAGEL, a citizen of the Republic of Hungary, residing at Portland, in the county of Multnomah and State of Oregon, have invented a new, original, and ornamental Design for an Emblematic Stand, of which the following is a specification, reference being had to the accompanying drawing, forming part thereof.

In said drawing the figure is an elevation of my said design arranged in the form of a stand.

The essential feature of my design consists of the representation of a globe supported on a base comprising diverging arms, and a band arranged centrally and crosswise of the globe.

I claim:

The ornamental design for an emblematic stand substantially as shown.

JOSEPH HUFNAGEL.
